UNITED STATES PATENT OFFICE.

EUGENE W. WALSH, OF NEW YORK, N. Y.

DOOR.

1,212,591.

Specification of Letters Patent. Patented Jan. 16, 1917.

Application filed September 11, 1915. Serial No. 50,145.

To all whom it may concern:

Be it known that I, EUGENE W. WALSH, a citizen of the United States, and a resident of New York, in the county of New York 5 and State of New York, have invented certain new and useful Improvements in Doors, of which the following is a specification.

This invention relates to improvements in doors and particularly to that type of doors 10 which are adapted to fold into small compass.

One of the objects of the invention is to provide a door capable of being easily and noiselessly operated by a light pressure applied in the desired direction, without danger of pinching the person or garments of 15 an operator.

A second object is to provide a door that is substantially sound-proof by reason of 20 its overlapping side elements, and finally to provide a door of neat appearance, strong yet light, and relatively inexpensive in its construction.

These and similar objects, which will be 25 come more fully apparent as the description progresses, are attained by the novel structure herein set forth and shown in the annexed drawing which forms part of the disclosure.

30 In the drawing:—Figure 1 is a front elevation of a door made in accordance with the invention. Fig. 2 is an enlarged transverse sectional view, taken on line 2—2 of Fig. 1. Fig. 3 is a similar view of 35 the same, showing the door elements in a folded position. Fig. 4 is a further enlarged fractional front view, and Fig. 5 is a plan view of an element used in connection with the center joint rod.

40 The drawings illustrate the application of a door to a narrow chamber or room, such for instance as a telephone booth, where it is desirable to have a door that can be quickly operated, both in opening and closing, without noise, jar or vibration, that will stay in the position in which it is placed and which, when folded or opened, occupies a minimum of space.

Referring to the drawing, the side walls 50 of the chamber are indicated by the numerals 10 and 11, respectively right and left, to which the front walls 12 and 13 are joined as shown, and it will be evident that these

front walls also constitute the jambs of the door.

The door is comprised of two main elements 14 and 15 which may be furnished with panels 16 and 17 of glass if preferred.

The stile 18 of the door element 14 has on its outer side a flange 19, overhanging the jamb 12 when the door is closed, on the opposite side of the stile 18 are hinges 20, the joint 21 of which is set back from the edge so as to permit the flange 19 to swing past the corner of the door jamb. Between the 65 hinges is a longitudinal cleat 22 secured to the inner side of the stile 18 in such manner as to completely cover the joint opening between the stile and jamb when the door is closed, thus affording a double protection 70 against the transmission of sound.

The opposite stile 23 has a beveled recess 24 extending its full length, terminating laterally in a beading 25 and the stile 26, of the adjoining door element 15, has a similar 75 beveled recess 27 and bead 28. To these beveled surfaces are attached the straps 30 of the connecting hinges, the pivot joint 31 of which is substantially in the vertical plane of the front of the doors.

80 The front stile 32 of the door element 15 has a bevel 33 formed on its outer edge to suit the shape of the jamb 13 and is also formed with an extending flange 34 adapted, when the door is closed, to make contact 85 with the jamb; further protection against the passage of sound is provided by the cleat 35 secured to the inner side of the jamb 13. In order to cause the door to properly operate in a predetermined path, a radius 90 rod is pivoted within the room or booth, the front end 38 of the rod being pivoted to a bracket 39, secured at the inner side of the door element 15 near the top.

95 It is to be noticed that the narrow adjacent edges of the stiles 23 and 26 are formed concavely to a radius coincident of the hinge joints 31; this radius extends the full length of both stiles and has suited to it rods of appropriate length to fill the space 100 between the hinges and also at the top and bottom of the door, the rods being of the same diameter as the hinge joint. In place of the usual pin at these joints, special pins 105 41 are used the same being extended at both ends beyond the hinges and entered into the

rods 40 as shown thereby holding them in register, close to, but clear of the stiles.

A further guiding means for the rods is provided in the plates 42 secured to the top 5 and bottom of the door upon each of its elements and having an opening 43 to receive a pintle formed with the corresponding ends of the extreme rods. Thus the rods are arranged to close the opening otherwise 10 existing between the door sections notwithstanding the position the sections may be in, effectually preventing the issuance of sound or the possibility of engaging the clothing or fingers in the opening.

15 In operation, when the door is closed, as shown in Fig. 2, pressure may be applied to the elements 23, 26 or 40, whereupon these parts move back or inwardly, turning on the hinges 31; this causes the door element 20 14 to swing upon the hinges 21 and at the same time the stile 32 is moved forward or outward as the door element 15 cannot move back but is caused to pivot at the point 39. This action continues until the door elements 25 fold together, the rod 38 at that time swinging toward the right until the parts come into the position shown in Fig. 3.

Pressure applied from the interior against the rod 40 or from the outside against the 30 stile 32 causes the door to close.

The entire absence of rollers, wheels, trackways, etc., eliminates the noise which is otherwise created and it will be evident that the movement is smooth and easy. Also 35 that when the door is closed that there exists at each edge a double means for preventing the transmission of sound, besides that at the center.

Copies of this patent may be obtained for five cents each, by addressing the "Commissioner of Patents, Washington, D. C."

Having thus described my invention, what I claim as new and desire to secure by Letters Patent, is:—

1. In a door, the combination with a pair of folding elements each beveled at the joint on the inner side thereof, of cylindrical joint hinges having leaves attached to the 45 beveled edges of said elements, the cylindrical portion of each of said hinges being disposed in the plane of the front of said door elements, pivot pins carried by said hinges and extending therefrom, cylindrical joint rods registering with and forming 50 continuations of the cylindrical portion of said hinges, said rods being separate from the door elements and filling the unoccupied spaces along the edges thereof.

2. A folding door comprising two main elements, one being hinged to a door jamb, the other having an edge mating the opposite jamb, a cleat attached to the hinged elements and so located as to cover the joint between said element and the jamb when the door is closed, a second cleat attached to the interior of the opposite jamb whereby the joint thereat is covered when the door is closed, flanges extending from each of said door elements and so located as to cover the joints at the outer sides of the jambs when the door is closed, hinges disposed between said door elements and connected thereto, and means combined with the hinges whereby the joint between said door elements is covered.

In testimony whereof I have signed my name to this specification.

EUGENE W. WALSH.
